UNITED STATES PATENT OFFICE.

JOSEPH A. SHOEMAKER, OF NEW YORK, N. Y.

GARMENT-HANGER.

1,377,444.

Specification of Letters Patent. Patented May 10, 1921.

Application filed September 5, 1919. Serial No. 321,867.

To all whom it may concern:

Be it known that I, JOSEPH A. SHOEMAKER, a citizen of the United States, and a resident of New York, in the county of 5 Kings and State of New York, have invented certain new and useful Improvements in Garment-Hangers, of which the following is a full, clear, and exact description, whereby any one skilled in the art may 10 make and use the same.

The invention relates to garment hangers and might perhaps better be termed a "garment hanger support" inasmuch as the garments are indirectly supported upon the device herein described through any usual 15 form of garment hanger.

It is analogous to devices disclosed in my prior applications, but is a simplification thereof, with certain features of advantage 20 in operation and improvements in form which give advantages in folding, etc.

In my prior devices, I have usually provided a structure in which there is a distinct vertical strut coöperating with a lateral 25 strut, with an adjustable supporting bar intermediate the strut members.

In these prior devices, a vertical strut has been formed by a connection intermediate 30 the supporting point for the hanger and the adjustable tension member of the strut. Such a device is illustrated in my Patent No. 1,293,953 dated Feb. 11th, 1919.

In the invention hereinafter disclosed, I have condensed the vertical strut, maintaining 35 the lateral strut members and provided for a folding in of the parts, one within the other, which gives an extremely compact and efficient device and one which may be manufactured at an extremely low cost due to 40 the reduction of a number of parts.

Referring to the drawings:

Figure 1 illustrates the device extended in its supporting position.

Fig. 2 illustrates the device folded.

Fig. 3 is a rear end view.

Fig. 4 is a detail view of the adjusting device for the vertical strut members.

Fig. 5 is a detail view of a modified form of structure.

Fig. 6 is a detail view of the support and the loop.

Fig. 7 is a detail view of the lateral arms.

Fig. 8 is a rear end view of the support.

Fig. 9 is an illustrative view showing the 55 application of the hanger to a closet door.

Fig. 10 is a view showing in open and

folded positions the supporting ring in slightly modified form.

In my co-pending application, I provide a flexible tension member between the point 60 of support and the end of an adjustable compression member, the two forming a vertical strut for a hanger, which is coöperatively related with foldable arms which bear against the wall and serve as a lateral strut. 65

In the device herein disclosed, I maintain the telescopic features of the compression member which forms the support of my prior application, but secure advantageous results by utilizing a telescopic member, one 70 end of which is rigidly supported from a hook or bracket, with folding lateral strut members which may be adjusted from the end of the telescoping support.

In the accompanying drawings, 1 denotes 75 a tubular supporting member telescopically arranged with reference to a coöperating tube 2. These two members comprise the main supporting bar, one of which is drawn down or "bottle-necked" with reference to 80 the other to prevent withdrawal of the tubes one from another. The outer end of the tube 2, is closed by a finishing button 3, of proper design to prevent clothes hangers from slipping endwise from the device. 85

The tubular member 1, has secured to it a sleeve 4, threaded to receive an adjusting nut 5.

The sleeve 4, has extended lugs 6, 7, through which extends a supporting bar 8, 90 having at its upper end a suitable loop 9, for attachment to a wall-hook or nail. This bar 8, intermediate the members 6, 7, also forms an abutment against which the lateral extending arms 10, 11, are forced by the nut 95 5, to give the proper angular adjustments to the arms 10, 11, and cause them to engage the wall surface to give the required support to the telescoping tube 1, 2.

The arms 10, 11, are joined at their inner 100 ends by a pivot loop 12, so that they may be folded upon one another and inserted within the tubular members 1, 2, when the latter are collapsed.

The operation of the device will be quite 105 apparent. The telescoping members 1, 2, may be adjusted with reference to each other to give a greater or lesser length to the main supporting bar. The lateral strut members 10, 11, are withdrawn from the 110 interior of the tube until their inner ends or connecting link 12, abuts against the sup-

porting bar, 8. Thereupon, the nut 5, is adjusted against the edges of the bar 10, 11, until they are firmly engaged with the wall surface.

5 It will be apparent that a considerable angular adjustment is thus made possible for the arms 10, 11.

In order to secure a closer folding of the parts, the loop 9, may be arranged as indicated to fold down over the end of the tube upon partial rotation thereof. This, of course, requires a joint between the supporting member 8, and loop 9, or other suitable pivotal arrangements for permitting folding 15 of the loop. The arrangement illustrated is a convenient and efficient one. In this, the loop 9, has a laterally extended foot 9^a, and the loop is pivoted as at 8^a, to the supporting member 8, the arrangement 20 being such that the foot 9^a, abuts against the upper side of the extension 6, with the loop extended, and permits turning of the loop with the foot, so that the loop may be folded down over the end of the tube.

25 In Fig. 5 and the succeeding figures, there is illustrated a form of the device having certain simplifications and, possibly, advantages, the main features illustrating merely a reversal of the position of the telescopic members of the supporting bar. In these 30 figures, the tubular member 25, slides over the tubular member 26, there being a bottlenecking of the tube 25, at its end, as at 25^a, to prevent complete longitudinal disengagement of the tubes.

35 In place of having an independent sleeve or bracket member, as indicated in the form of device heretofore described, a section adjacent to the end of the tube 26, is threaded 40 as at 27, to receive a knurled threaded sleeve 28.

The end of the tube 27, is provided with 45 slots 29, 30, which form guides and supports for the laterally extendible arms 31, 32.

50 These arms are loosely pivoted together by a stud 33, which, with the arms extended, will bear against the supporting stud or member 34.

55 This member 34, has a head 35, provided with a slot 36, and below the head is screw-threaded, as at 37, to engage a threaded opening 38, in the upper section of the tube 26. The lower end of the stud 34, may be riveted over as at 39, where it passes through the lower portion 40, of the tube which extends between the slotted openings 29, 30.

60 A supporting loop or ring 41, passes through the slot 36, of the head 35, and preferably has a web 42, which, when passed into the slot 36, will prevent folding down of the loop 41, giving a substantially rigid connection between the loop 41, and the arm of the hanger. By partial rotation of the 65 loop 41, the web may be passed out of the

slot 36, and thereupon the loop may be turned down over the end of the tubular member 26.

It will be observed that the slots 29, 30, coöperate with the arms 31, 32, sleeve 28, 70 and supporting stud 34, to give a very substantial support and adjustment and permit locking of the parts firmly to any desired adjustment or position on the wall.

In either form of the device hereinabove 75 described, there are certain main essentials, whether the device is formed exactly as illustrated or in some modified arrangement, and whether tubular members are utilized for the supporting bar or other inter-engaging forms of structure are employed. These main elements, in their function, comprise a longitudinally adjustable supporting bar, having at its inner end extensible and 80 adjustable arms, providing a lateral support, combined with a supporting element and a means for holding the lateral arms to any desired adjusted position.

Incidentally, the lateral arms are made foldable and insertible with reference to the 85 supporting bar, and the supporting device or loop may also be made foldable, so that the device as a whole is at once most compact and yet forms an extremely suitable structure when the parts are extended and 90 adjusted to position.

What I claim as my invention and desire to secure by Letters Patent is:

1. A folding clothes hanger for supporting a plurality of garment hangers on a hook 100 or the like, comprising a supporting bar formed of telescoping members, a support for said supporting bar at one end thereof, adjustable arms foldable within and providing a lateral support for the bar in conjunction 105 with its support, and means adjustable with reference to the bar and lateral arms for locking the parts in adjusted position.

2. A folding clothes hanger comprising a 110 supporting bar formed of telescoping members, means for preventing longitudinal disengagement of the members, a support for said bar at one end thereof, adjustable arms sliding within the bar and providing when extended a lateral support therefor, and 115 means adjustable with reference to the bar and lateral arms for locking the parts in adjusted position.

3. A folding clothes hanger comprising a 120 supporting bar, a support for said bar at one end thereof, arms providing an adjustable lateral support for the bar when extended and foldable into the longitudinal line of said bar, and means adjustable with reference to the bar and lateral arms for locking 125 the parts in adjusted position with the arms extended at various angles to plumb the bar with reference to its support.

4. A folding clothes hanger comprising a 130 supporting bar, a support for said bar ex-

tending at right angles thereto, means for preventing folding of said support, from a position at right angles to the supporting bar, though permitting a folding of the support upon partial relative rotation of the support upon the bar.

5. A folding clothes hanger comprising a supporting bar formed of telescoping members, having means to prevent longitudinal disengagement, a support for said bar at one end thereof, adjustable arms extendible from within the bar providing a lateral support for the bar in conjunction with its support, guides formed in the supporting bar to confine the movement of the arms, and means adjustable with reference to the bar and arms for locking the parts in adjusted position.

6. In a device of the character described, having a supporting bar, a support for the bar consisting of a supporting member at right angles to the bar and a loop rotatable with reference to the supporting member, means appurtenant to the loop and supporting member for positively holding said parts in extended alignment, said means permitting a folding of the loop with refer-

ence to the supporting member upon partial relative rotation.

7. A folding clothes hanger comprising a supporting bar formed of telescoping members, a support for said supporting bar, a threaded adjusting ferrule engaging the support adjacent to one end, arms foldable within the bar and adapted when extended to form a lateral support therefor, and adapted when extended to be engaged and held to adjusted position by the threaded ferrule.

8. In a device of the character described, a supporting bar of tubular form, a support for said bar, adjustable arms providing a lateral support for the bar and slidable within the tubular bar, slots formed in said tube through which the lateral arms extend, and a ferrule adjustably engaging the bar and adapted to bear against the laterally extended arms for holding the parts in adjusted position.
